UNITED STATES PATENT OFFICE

HENRY H. BLAU, OF CHARLEROI, PENNSYLVANIA, ASSIGNOR TO MACBETH-EVANS
GLASS COMPANY, OF CHARLEROI, PENNSYLVANIA, A CORPORATION OF PENN-
SYLVANIA

DESIGN FOR A GLOBE

Application filed December 1, 1932. Serial No. 46,273. Term of patent 7 years.

To all whom it may concern:

Be it known that I, HENRY H. BLAU, a citizen of the United States, residing at Charleroi, in the county of Washington and State of Pennsylvania, have invented a new, original, and ornamental Design for Globe, of which the following is a specification, reference being had to the accompanying drawing, forming a part hereof.

Figure 1 is a top plan view of a globe showing my new design, and Figure 2 a side view thereof.

I claim:

The ornamental design for a globe, as shown.

HENRY H. BLAU.
